RECORDING APPARATUS

Frank T. John, State College, Pa., assignor to The Pennsylvania Research Corporation, State College, Pa., a corporation of Pennsylvania

Application April 3, 1952, Serial No. 280,405

3 Claims. (Cl. 346—50)

1

This invention relates to recording apparatus and, more particularly, to a writing mechanism for marking ink lines or traces on a record receiving member in response to electrical or mechanical impulses controlled by the occurrence of the event to be recorded.

It is among the objects of this invention to provide apparatus of the foregoing type for recording one or more ink lines or traces on a record receiving member, in which the writing elements have a very low inertia, so as to be quickly responsive to a minimum amount of applied power, and are made of inexpensive material that is easily replaced when worn.

A further object is to provide such a recording mechanism that can be used in a multiple channel polygraph for selectively recording data received from a plurality of datum originating sources.

The recording apparatus of this invention includes one or more capillary writing strings, each of which is normally held out of contact with a moving record receiving member but may be brought into contact with that member by an electromagnetic or mechanical actuating means that is responsive to the occurrence of an event to be recorded. The writing portion of each capillary string is supplied with ink from an ink supply by capillary flow along the string, so that when the string is brought into contact with the record receiving member, it will produce a continuous ink line or trace thereon.

The invention is illustrated in the accompanying drawings, in which Fig. 1 is a somewhat diagrammatic elevation of apparatus embodying the invention, and Fig. 2 is a plan view of a portion of the apparatus in Fig. 1.

Referring to Fig. 1 of the drawings, the record receiving member is represented by a strip of paper of any desired width, which extends from a paper-supply roll 2 to a take-up roll 3. Between those two rolls, the paper passes around a platen roll 4 and over two idler rolls 6 and 7. During the operation of the device, the paper is moved at a uniform rate over those rolls by conventional means, which are not illustrated and need not be described since they are not part of this invention.

The writing element is a capillary string 8, usually one of a plurality of such strings, made of any suitable capillary material, such as woven textile fibers. It is mounted below the platen roll 4 and at right angles to that roll, but normally out of contact with the paper passing around it. One end of this string is fastened to a

2

tension coil spring 9, mounted on a bracket 11; and the other end is secured to an armature 12 of a solenoid 13. At an intermediate point, the string is fastened to the end of a rotatable lever 14 carried by a pulley 15 on a shaft 17. Preferably, the lever 14 is normally so positioned that a substantial length of the string, including the writing portion thereof, is in contact with a supply of ink, for example, a sponge rubber pad 18 supported in an ink-containing reservoir 19, which may also be mounted on bracket 11. When the string is in its normal, lowered position, the weight of the armature 12 is sufficient to keep it under slight tension and in ink-absorbing contact with the sponge rubber pad 18, so that the writing portion of the string is kept thoroughly inked when not in use.

Solenoid 13 is energized by an electrical circuit 21 that is responsive to the happening of the event to be recorded. For simplicity, that event may be represented by the manual closing of a switch 22 in that circuit. When the switch is closed, the solenoid is energized in a manner to cause a downward electromagnetic force on the armature. As the latter moves downward in response to such force, it pulls the string with it against the urging of the spring 9. This longitudinal movement of the string rotates lever 14 about the shaft 17, thereby raising the writing portion of the string from the ink pad 18 into contact with the paper where the latter passes around the platen roll 4. The position of the string in its writing position is shown by the broken line in Fig. 1. On making contact with the paper, the string will immediately mark an ink trace thereon, since the writing portion of the string has previously been in contact with the ink pad and is already saturated with ink. As the paper is continuously moved around the platen roll, the trace left by the string becomes a straight line, the length of which measures the duration of the event to be recorded, in this case, the time during which switch 22 remains closed.

In order to assure a continued flow of ink when the string is in prolonged contact with the paper, platen roll 4 is so spaced from the ink pad 18 and that pad is of such a width that a portion of the string will remain in contact with the pad after the string is raised into its writing position. Since the ink in the reservoir 19 keeps the ink pad saturated, the latter, in turn supplies a constant flow of ink to the capillary string.

When the circuit 21 is opened by the opening of the switch 22, the solenoid 13 is deenergized and the only downward force applied to the

armature 12 is that of gravity, which is not sufficient to maintain the lever 14 in its raised writing position against the urging of spring 9. Accordingly, the lever and string return to their normal positions with the string across the top of the ink pad 18, awaiting the next writing operation.

Ordinarily, more than one writing string will be used, in order to mark on the record receiving member data supplied by a plurality of datum originating sources. It will be obvious that many strings can be supported in spaced parallel relation to each other, as shown in Fig. 2, each string being connected to a separate lever 14 and being actuated by its own solenoid 13, which is in turn controlled by its own electrical circuit that is responsive to a particular datum source. A single ink pad 18 and a single ink reservoir 9 may be used to supply ink to all of the strings. Likewise, the shaft 17 may be common to all of the levers 14 and pulleys 16. Apparatus of this type, employing a plurality of capillary strings, can be used as the writing or recording mechanism of a multiple channel polygraph, in which data from a large number of datum originating sources can be selectively and simultaneously made on a single record receiving member.

It is among the advantages of this invention that the capillary writing strings have a very low inertia, so that they are quickly moved into writing position with a minimum amount of applied power. A further advantage is that the writing portion of each capillary string is always saturated with ink and ready for immediate use, thereby avoiding the cleaning and priming operations so often required when using conventional glass pens as the writing elements. Again, if any string becomes worn after continued use, it may be easily and cheaply replaced.

In order to prevent the flow of ink from the capillary string beyond the writing portion of that string, where no ink is required, it may be desirable to apply to the string a coating of shellac, or other substance, that will interrupt the capillary flow of the ink. For example, a portion of the string adjacent the end of the lever 14 can be impregnated with shellac. It will be understood, of course, that it will be equally feasible to have the capillary string end at the point of attachment to lever 14 and to be connected at that point to a non-capillary string or flexible wire, which is in turn attached to the armature 12 of the solenoid. Accordingly, the term "capillary string," as used in the attached claims, is intended to include a compound string of this type in which the writing portion of the string alone has capillary properties.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. A recording apparatus for recording data from a datum originating source onto a record receiving member, comprising a capillary string normally supported in spaced relation to the record receiving member, a tension spring connected to one end of the string for yieldably supporting that end, a rotatable lever engaging an

intermediate portion of the string and adapted when rotated to cause a portion of the string to contact the record receiving member, electromagnetic means connected to the other end of the string for rotating the lever by exerting tension on the string, an ink supply normally contacting the string, and an impulse receiving circuit responsive to the datum originating source for energizing said electromagnetic means, thereby causing the lever to rotate and bring a portion of the string into writing contact with the record receiving member.

2. A recording apparatus for selectively recording data from a plurality of datum originating sources onto a record receiving member supported by a platen roll, comprising a plurality of capillary strings supported in spaced parallel relation to each other and at right angles to the platen roll and normally spaced from the record receiving member, tension spring means connected to one end of each string for yieldably supporting that end, a separate rotatable lever connected to each string and adapted when rotated to move a portion of the string into contact with the record receiving member, separate electromagnetic means connected to each lever for rotating the lever when energized, a supply of ink contacting each string, a plurality of separate impulse receiving circuits, each circuit including one of said electromagnetic means and each being responsive to a particular datum originating source, whereby an electrical impulse in one of said circuits will energize the included electromagnetic means to cause one of said strings to contact the record receiving member and mark an ink trace thereon.

3. A recording apparatus for selectively recording data from a plurality of datum originating sources onto a record receiving member supported by a platen roll, comprising a plurality of capillary strings supported in spaced parallel relation to each other and at right angles to the platen roll and normally spaced from the record receiving member, tension spring means connected to one end of each string for yieldably supporting that end, a separate rotatable lever connected to an intermediate point on each string and adapted when rotated to move a portion of the string into contact with the record receiving member, separate electromagnetic means connected to the other end of each string for rotating the lever connected to the string by exerting tension on the string, a supply of ink normally contacting the writing portion of each string and remaining in contact with another portion when the string is in its writing position, a plurality of separate impulse receiving circuits, each including one of said electromagnetic means and each being responsive to a particular datum originating source, whereby an electrical impulse in one of said circuits will energize the included electromagnetic means to cause one of said strings to contact the record receiving member and mark an ink trace thereon.
